R. ACKERMAN.
CLAMPING DEVICE FOR DRINKING BOWLS.
APPLICATION FILED OCT. 7, 1920.

Patented Sept. 12, 1922.

INVENTOR

ROBERT ACKERMAN
BY HIS ATTORNEY.

James F. Williamson

UNITED STATES PATENT OFFICE.

ROBERT ACKERMAN, OF MINNEAPOLIS, MINNESOTA, ASSIGNOR TO HUDSON MANUFACTURING COMPANY, OF MINNEAPOLIS, MINNESOTA, A CORPORATION OF MINNESOTA.

CLAMPING DEVICE FOR DRINKING BOWLS.

Application filed October 7, 1920. Serial No. 415,872.

To all whom it may concern:

Be it known that I, ROBERT ACKERMAN, a citizen of the United States, residing at Minneapolis, in the county of Hennepin and State of Minnesota, have invented certain new and useful Improvements in Clamping Devices for Drinking Bowls; and I do hereby declare the following to be a full, clear, and exact description of the invention, such as will enable others skilled in the art to which it appertains to make and use the same.

This invention relates to clamping means in which the wall of a receptacle is clamped between an interior and an exterior member. The specific embodiment of the invention selected for illustration portrays the invention as applied to the bowl of a drinking fountain designed for the use of animals.

It is an object of this invention to provide a device by which a bowl or other receptacle may be securely clamped in position so that the same may be readily removable.

It is also an object of the invention to provide clamping means which will securely clamp a bowl or other receptacle in such a manner that the same will not be unduly worn or abraded. These and other objects of the invention will appear as the device is further described in connection with the accompanying drawing, in which

The figure is a perspective view of the device with the bowl or receptacle to be clamped shown in section.

Referring to the drawings, the numeral 1 designates a post, or other suitable support to which a drinking bowl, or other receptacle is to be secured. Secured to the member 1 by screws 2, or other suitable means, is a bracket 3 which has connected thereto, by integral, or other means, one part 4 of a two-part nozzle, the other part of which is shown at 5. The two parts of the nozzle are separably arranged and shown as connected in operable position by a clamping screw 6. This nozzle extends into a bowl or receptacle 7. The lower part of the member 5 carries a bifurcated or apertured portion 8 forming a seat for the pivot 9 of an operating member 10, which is disposed some distance

above the bottom of the receptacle 7. The member 10 is connected to a nozzle valve, (not shown) in any suitable manner, so that the depression thereof will operate the valve and allow water or other liquid to be discharged into the receptacle 7. A pipe shown in section as 11 may be suitably connected to the nozzle and to any desired water supply. Depending from the bracket 3 and spaced from the member 4 is a lug 12. A threaded aperture in this lug is designed to receive a clamping screw 13 having a head 14 thereon. Secured to the member 4 by pivots 15 and ears 16 at each side thereof, is a depending member 17 which extends between the lug 12 and the part 4 of the nozzle. The part of this member 17 which is disposed toward the part 4, is shaped to approximately the same contour as the exterior of the receptacle 7. The clamping screw 13 is arranged to contact with the member 17, and by tightening this screw, the wall of receptacle 7 is firmly clamped between this member and the part 4 of the nozzle.

By having the member 17 disposed between the screw 13 and the wall of member 7, contact of the screw end with the receptacle wall is avoided and the wall is thus not abraded or worn, as would be the case if the screw made contact directly with the wall.

It is thus seen that applicant has provided an efficient and simple clamping means and one that is especially adapted for the purpose described and illustrated. Stated generally, the invention consists in the matter shown and described and specifically set forth in the appended claims.

What I claim is:

1. A drinking fountain structure comprising, a bowl, a nozzle forming pipe extending into said bowl, a bracket supporting said pipe, a clamping member pivoted to the side of said pipe, said pipe being formed to contact the inner surface of the bowl adjacent the top thereof, and said clamping member being formed to contact the outside surface of the bowl adjacent the top thereof, said bracket having a downwardly extending lug adjacent said clamping member, and a screw passing through said lug and engaging said

clamping member to clamp the bowl between the same and said pipe.

2. A drinking fountain structure having in combination a bowl, a bracket having a nozzle secured thereto, said nozzle extending into and contacting with the inner surface of the bowl, means in said bowl co-operating

with said nozzle to control the flow of water into said bowl, a lug pivoted to said nozzle, and means carried by said bracket co-operating to clamp the bowl between said lug and said last mentioned means. ¹⁰

In testimony whereof I affix my signature,
ROBERT ACKERMAN.
